United States Patent Office.

WILLIAM P. SKIFFINGTON, OF NEW YORK, N. Y.

Letters Patent No. 103,248, dated May 17, 1870.

IMPROVEMENT IN STEAM-GENERATORS.

The Schedule referred to in these Letters Patent and making part of the same.

To all whom it may concern:

Be it known that I, WILLIAM P. SKIFFINGTON, of New York, in the county and State of New York, have invented certain new and useful Improvements in "Steam-Boiler," of which the following is a specification.

Figure I represents a longitudinal horizontal section of a steam-boiler embodying my invention.

Figure II is a cross-section.

Figure III is a vertical longitudinal section of parts of boiler.

My invention consists in the construction of square boxes A, each box having all the ends of the tubes forming one row attached to it.

These boxes A have openings n m running nearly their whole length at top and bottom, leaving suitable flanges w all around on their inner part, through which bolts v pass to screw one box to the other box.

Besides these openings n and m, an opening, x, is made at the end of each box, extending nearly the whole length of the box, or the width of one row of tubes, and closed by a suitable plate or cover, h.

The tubes may be fastened in various way to these boxes, but I prefer to attach to the ends of the tubes B flanges a, and to fasten the same, by means of bolts, against the boxes A.

By this arrangement, the circulation of the water

and steam at the ends of the tubes in those boxes will not be confined or obstructed, as the area of the openings n and m will be larger than the area of several of the tubes, and the tubes can be easily cleaned and repaired through the doors or covers h.

In the manufacture of boilers after this plan the number of pieces is reduced, and, as each row of tubes forms a complete part, the required size of a boiler can be readily obtained by increasing or diminishing the number of rows.

The box on the upper or lower row may either be made with the upper or lower ends cast in solid, or by fastening suitable covers to the same.

The sides and top of the boiler or fire-room are formed by brick-work, as represented in Figs. I and II.

What I claim as my invention, and desire to secure by Letters Patent, is—

The arrangement of boxes A with openings n, m, and x, the latter opening being closed by a suitable plate or cover, h, in combination with a series of tubes, B, and constructed substantially as and for the purpose herein described.

WILLIAM P. SKIFFINGTON.
